FUSE SETTING MACHINE

George W. Beatty, Decatur, Ill., assignor to Government of the United States of America, represented by the Secretary of War

Application May 21, 1937, Serial No. 143,941

7 Claims. (Cl. 86—23.1)

(Granted under the act of March 3, 1883, as amended April 30, 1928; 370 O. G. 757)

The invention described herein may be manufactured and used by or for the Government for governmental purposes, without the payment to me of any royalty thereon.

The subject of the invention is a fuse setting machine.

The invention is an improvement on the fuse setting machine shown in Patent No. 1,898,081, of February 21, 1933, in which two relatively rotatable adjusting members are arranged to be coupled to a fixed and a removable part of a fuse in a round of ammunition.

The improvements relate to a simple, compact, and efficient arrangement of means for locking and unlocking one of the adjusting members, of means for controlling release of the round-actuated plunger, and of means for controlling the operation of a round-holding latch.

To these and other ends, the invention consists in the construction, arrangement and combination of elements described hereinafter and pointed out in the claims forming a part of this specification.

A practical embodiment of the invention is illustrated in the accompanying drawings, wherein:

Fig. 1 is a longitudinal sectional view of the improved fuse setter with the parts in normal position.

Figs. 2, 3 and 4 are sectional views on the corresponding lines of Fig. 1.

Fig. 5 is an enlarged view of the round-holding latch.

Fig. 6 is a sectional view on the line 6—6 of Fig. 1, with a round of ammunition inserted in the machine.

Fig. 7 is a similar view without the round and showing the parts in the normal position.

Figs. 8, 9 and 10 are views of the bolt respectively in plan and in side and front elevation.

Fig. 11 is a sectional view on the line 11—11 of Fig. 6.

Fig. 12 is a sectional view on the line 12—12 of Fig. 6.

Figs. 13 to 16 are detail views showing various relationships of the bolt and the retracting and latch bars.

Fig. 17 is a view in side elevation of the front end of a round of ammunition.

The fuse setter comprises a housing 5 adapted to be fixed to a base A and to carry a casing 6 which is mounted on a hinge pin 7 and locked to the housing in any suitable manner. The casing includes a flared mouth 8 to facilitate introduction of a round of ammunition B.

Within the housing 5 and casing 6 are respectively mounted adjusting members 9 and 10 which are independently rotatable about the axis of the machine. The member 9 is adapted to be coupled to the rotatable time ring C of the fuse D and carries a spring pressed pawl 11 (Fig. 3) for entering a notch 12 in the ring C. The member 10 is to be similarly coupled to a fixed part of the fuse and carries a spring pressed pawl 13 (Fig. 2) for entering a notch 14 in the fuse.

The adjusting member 9 includes a worm wheel 15 whereby it is driven from a worm 16 on an operating shaft 17. A bevel gear 18 on the adjusting member 9 drives a bevel gear 19 on a shaft 20 which leads to suitable mechanism for indicating the amount of rotation or the angular position of the actuating member. The adjusting member 10 includes a bevel gear 21 meshing with a bevel gear 22 (in Fig. 6) on an operating shaft 23 controlled by a handwheel 24.

A plunger 25 is disposed axially within the adjusting member 9 with its front portion supported by an internal rib 26 of the adjusting member and its intermediate portion supported by the hub 27 of the housing 5 while its rear portion is supported through a sleeve 28 fixed thereon and slidably in an end cap 29 on the housing. A guide tube 30 inserted partially within the plunger extends through the end cap 29 and is surrounded by a spring 31 which is confined between the end cap and a head on the inner end of the tube. The spring normally holds the plunger in the forward position (Figs. 1 and 7) with the sleeve 28 engaging the rear face of the hub 27. The front end of the plunger is formed with a recess 32 for receiving the nose of the fuse D, and when the round of ammunition is fully inserted the plunger is moved against the action of the spring 31 until the shoulder 33 of the plunger engages the front face of the hub 27 (Fig. 7).

A pivoted latch 34 (Figs. 1 and 5) mounted in a slot 35 in the plunger has a hook 36 on its front end which is adapted to enter the recess 32 and engage in a groove 37 in the fuse for the purpose of holding the round of ammunition against removal. A laterally projecting finger 38 on the latch is arranged to engage the rib 26 of the adjusting member 9 when the plunger is in the normal forward position (Fig. 1) so that the hook 36 will be maintained out of the recess 32. Upon retraction of the plunger the finger 38 encounters a spring-pressed plunger 39 (Fig. 5) in the hub 27 and is moved about its pivot so that the hook

enters the recess 32 to engage in the groove 37 of the fuse.

The housing 5 is formed with a channel 40 (Figs. 7 and 11) one side of which is closed by a plate 41 secured to the housing by screws 42. A bolt 43 slidably mounted in the channel is formed with a passage for receiving a spring 44 which is seated on one prong of a bifurcated lug 45 on the plate 41. The spring normally urges the bolt towards the adjusting member 10 so that the front end of the bolt may enter the recess of a keeper 46 (Figs. 6, 7, 11 and 12) which is attached by means of rivets 47 to a disk 48 on the adjusting member 10. The keeper is formed with a projecting lip 49 and the periphery of the disk includes on opposite sides a front cam 50 and a rear cam 51.

The upper wall at the front end of the bolt (Figs. 8, 9 and 10) is provided with a beveled surface 52 adapted to engage a correspondingly beveled seat 53 in the keeper. The upper portion of the outer side of the front end of the bolt is formed with a notch 54 for receiving a hook 55 on a bar 56. This bar is supported on a lug 57 (Fig. 12) of the casing 6 and on the upper prong of the lug 45 of the plate 41 while its rear end is pivotally attached to the outer end of an arm 58 which is disposed in the end cap 29 and fixed on the sleeve 28 that forms part of the plunger 25. As a result of this connection the bar partakes of the reciprocating movement of the plunger and serves to retract the bolt from the keeper. The bar is acted on by a spring 59 carried by the plate 41 and is normally held thereby in contact with the side of the bolt.

The hooked end of the bar is formed with a transversely disposed slot 60 (Fig. 13) which is provided to permit passage of the rear cam 51 during the first revolution of the adjusting member 10 when the hooked end of the bar is still in engagement with the bolt. The face 61 of the hooked end which is on the outer side of the slot 60 is disposed in the path of the front cam 50 (Fig. 14) so that, as the adjusting member 10 nears the termination of its first revolution, the cam will engage the face 61 and move the bar 56 to disengage the hook 55 from the notch 54 of the bolt.

The hook, in moving out of engagement with the notch, cams the bolt rearwardly a short distance to uncover the head 62 of a latch bar 63 which is arranged parallel to the bar 56 on the opposite sides of the lugs 45 and 57 and is pivotally attached to the prongs of the lug 45 of the plate 41. The latch bar 63 is acted on by a spring 64 carried by the plate 41 and when the head 62 is uncovered, the spring moves the latch bar towards the bolt to place the head 62 in front of the bolt, as seen in Fig. 14. The hook 55 in moving out of the notch 54 retracts the bolt a slightly greater distance than is necessary to uncover the head 62 and this provision is made so that the bolt, in moving into engagement with the head, will ride over the hook 55 (Fig. 14) and maintain the bar 56 in the disengaged position.

During the second revolution of the adjusting member 10, the rear cam 51 engages the head 62 (Fig. 15) of the latch bar and moves it out of engagement with the bolt 43. The bolt, now released, is moved by its spring into contact with the disk 48. When the further rotation of the disk brings the keeper 46 opposite to the bolt, the lip 49 on the keeper engages the bottom of the bolt and the bolt under the urge of its spring 75

enters the recess of the keeper and is brought up against the beveled seat 53.

A lever 65 (Fig. 11) is mounted near its center on a pin 66 in the bolt and has a turned front end 67 which is positioned at the front end of the bolt and which extends below the bottom face of the bolt when the rear end of the lever is elevated. The front end 67 is adapted to be struck by the lip 49 of the keeper 46 when the bolt is bearing against the disk (Fig. 15) during the second revolution of the disk. When the lever 65 is actuated in this manner its rear end acts on a latch 68 to swing said latch about its pivot 69 and disengage its head from the arm 58 so that the plunger 25 will be released and be capable of returning to its initial and normal position when the round of ammunition is withdrawn.

The pivot 69 of the latch extends across a slot 70 in the rear wall of the end cap 29 while the shank of the latch extends through an opening 71 in the rear wall. The rear end of the latch is formed with oppositely extending arms 72 and 73, the arm 72 being acted on by a spring 74 to normally hold the latch in position to engage the arm 58 and the arm 73 being provided for manually disengaging the latch. A rod 75 extending through the rear wall of the end cap adjacent the latch 68 and attached to the arm 58, serves for manually retracting the plunger.

The parts are normally in the position shown in Figs. 1 and 7, the plunger 25 being fully forward, the bolt 43 being engaged in the recess of the keeper 46 to hold the adjusting member 10 against rotation, and the hook 55 of the retracting bar 56 being engaged with the bolt.

When a round of ammunition is inserted into the machine it strikes the plunger 25 and forces it to the position shown in Fig. 6 where it is held by the latch 68 while the round is held by the latch 34 as seen in Fig. 5. The bar 56 being attached to the plunger is also retracted and withdraws the bolt 43 from the keeper 46 to effect release of the adjusting member 10.

The adjustment of the fuse is accomplished by causing the adjusting member 10 to carry out two complete revolutions while the member 9 is either stationary or under continuous operation. When the member 10 is coupled to the body of the fuse D by means of the pawl 13 the round of ammunition will be rotated even though resistance is offered by the man holding the round.

Since the time ring C of the fuse is rotatable with the round the notch 12 of the time ring will sooner or later be in position to be engaged by the pawl 11 of the adjusting member 9. When this occurs the angular displacement of the time ring will be under control of the adjusting member 9 and it will assume an angular position relative to the predetermined position of the adjusting member 10. The purpose of turning the member 10 through two revolutions is to insure coupling of the adjusting members with the notches 12 and 14 irrespective of their position relative to each other and to the adjusting members at the commencement of the operation.

During the two revolutions of the adjusting member 10 the cams 50 and 51 on the disk 48 act on the retracting bar 56 and latch bar 63 in the manner outlined in connection with the description of Figs. 13 to 16 so that the adjusting member, at the conclusion of its second revolution will be engaged by the bolt 43 and the latch 68 will be actuated to release the plunger 25. The adjusting member 10 is held against initial move-

ment in the wrong direction by a pawl 76 (Figs. 1 and 4) mounted in the casing 6.

Upon withdrawal of the round the plunger 25 is moved forwardly by its spring and restores the bar 56 to its forward position so that it may re-engage the bolt and thereby be prepared to retract the bolt when the next round is inserted.

I claim:

1. In a fuse setting machine, a support, a pair of coaxial adjusting members rotatably mounted in the support, a disk on one of the adjusting members, a keeper on the disk and having a projecting lip, a pair of cams on the periphery of the disk, a plunger in the other adjusting member adapted to be retracted when struck by a round introduced into the machine, a latch for holding the plunger in retracted position, a bolt mounted in the support and having a notch, a spring for moving the bolt into the keeper, a retracting bar pivotally attached to the plunger and engageable with the notch of the bolt for withdrawing the bolt from the keeper, said bar movable out of engagement with the notch by one of the cams on the first revolution of the disk and further retracting the bolt, a latch bar pivotally mounted in the support and movable into the path of the bolt to be engaged by the bolt after partial forward movement thereof which blocks return of the retracting bar, said latch bar movable out of engagement with the bolt by the other cam, and a lever carried by the bolt and adapted to be actuated by the lip of the keeper to disengage the plunger-holding latch.

2. In a fuse setting machine, a support, a pair of coaxial adjusting members rotatably mounted in the support, a disk on one of the adjusting members, a keeper on the disk, a pair of cams on the periphery of the disk, a plunger in the other adjusting member adapted to be retracted when struck by a round introduced into the machine, a bolt mounted in the support and having a notch, a spring for moving the bolt into the keeper, a retracting bar pivotally attached to the plunger and engageable with the notch of the bolt for withdrawing the bolt from the keeper, said bar movable out of engagement with the notch by one of the cams on the first revolution of the disk and further retracting the bolt, a latch bar pivotally mounted in the support and movable into the path of the bolt to be engaged by the bolt after partial forward movement thereof which blocks return of the retracting bar, and said latch bar movable out of engagement with the bolt by the other cam.

3. In a fuse setting machine, a support, rotatable fuse and round adjusting members mounted in the support, a disk on the round adjusting member, a pair of cams on the disk, a plunger in the fuse adjusting member and adapted to be retracted when struck by a round introduced into the machine, a bolt mounted in the support and engageable with the disk for holding the round adjusting member against rotation, a retracting bar carried by the plunger and engageable with the bolt, said bar movable

out of engagement with the bolt by one of the cams on the first revolution of the disk, a latch bar carried by the support and replacing the retracting bar to hold the bolt, said latch bar movable out of engagement with the bolt by the other cam on the second revolution of the disk.

4. In a fuse setting machine, a support, rotatable fuse and round adjusting members mounted in the support, a plunger in the fuse adjusting member adapted to be retracted when struck by a round introduced into the machine, a latch for holding the plunger in retracted position, a bolt for holding the round adjusting member against rotation, means carried by the plunger for retracting the bolt, means on the round adjusting member and operable on the first revolution thereof to disengage the bolt retracting means, means replacing the retracting means for holding the bolt in retracted position, means on the round engaging member and operable on the second revolution thereof to disengage the bolt holding means, and means carried by the bolt for disengaging the latch from the plunger at the end of the second revolution of the round adjusting member.

5. In a fuse setting machine, a support, rotatable fuse and round adjusting members mounted in the support, a plunger in the fuse adjusting member adapted to be retracted when struck by a round introduced into the machine, a bolt for holding the round adjusting member against rotation, means carried by the plunger for retracting the bolt, means on the round adjusting member and operable on the first revolution thereof to disengage the bolt retracting means, means replacing the retracting means for holding the bolt in retracted position, means on the round engaging member and operable on the second revolution thereof to disengage the bolt holding means.

6. In a fuse setting machine, a support, rotatable fuse and round adjusting members mounted in the support, a plunger in the fuse adjusting member adapted to be retracted when struck by a round introduced into the machine, a latch for holding the plunger in retracted position, a bolt for holding the round adjusting member against rotation, and a lever carried by the bolt and adapted to be actuated by the round adjusting member to disengage the plunger-holding latch.

7. In a fuse setting machine, a support, a rotatable adjusting member in the support, a plunger in said member and adapted to be retracted when struck by a round introduced into the machine, a latch pivotally mounted in the plunger and adapted to hold the round, a projecting finger on the latch, means on the support for engaging the finger to move the latch into round-holding position and means on the adjusting member for engaging the finger to move the latch out of round-holding position.

GEORGE W. BEATTY.
